UNITED STATES PATENT OFFICE.

JAMES E. BENEDICT, OF WOODSIDE, MARYLAND.

PINWHEEL-SUPPORT.

SPECIFICATION forming part of Letters Patent No. 726,847, dated May 5, 1903.

Application filed September 25, 1901. Serial No. 76,555. (No model.)

To all whom it may concern:

Be it known that I, JAMES E. BENEDICT, a citizen of the United States, residing at Woodside, in the county of Montgomery and State 5 of Maryland, have invented certain new and useful Improvements in Pinwheel-Supports, of which the following is a specification.

My present invention pertains to improvements in pinwheel-supports, the construction 10 and advantages of which will be hereinafter set forth, reference being had to the annexed drawings, wherein—

Figure 1 is a perspective view of my improved device; Fig. 2, a sectional view of a 15 portion thereof, showing the pinwheel in position; and Fig. 3, a perspective view of the supporting shaft or spindle and its accompanying parts.

As is well known, the full effect and beauty 20 of a pinwheel in action is often marred or destroyed through lack of a proper support about which or with which it may rotate.

The object, therefore, of my invention is to provide a simple and efficient support for 25 a pinwheel, one which may be readily fastened to any object and which will enable the user to readily attach the pinwheel to the shaft or spindle and secure the shaft or spindle in position with relation to the support 30 proper.

In the drawings I have shown a piece of wire formed with a relatively short member A and a longer member B, the upper end of said longer member constituting an arm C, 35 provided with a point D. As will be noted, the members A and B stand substantially parallel throughout their length, being connected at their lower ends by a U-shaped section E. The arm B extends above the upper end of 40 arm A to a height sufficient to permit arm C to be readily driven into the object to which it is desired to attach the support. Formed in arm B is a socket or depression F, and upon arm A directly opposite said socket F 45 is a second socket G. Grooves or channels H I are formed in the face of member A and extend into the opening G.

J represents the shaft or spindle, herein shown as an ordinary needle, the head thereof 50 being seated in the recess or socket F and the point finding its bearing in recess or socket G. Secured to the needle, approximately at

mid-length thereof, is a disk or button K, constituting a stop for the pinwheel L. To hold the pinwheel against disk K, I employ a 55 washer, button, or the like. In the drawings there is shown a piece of cork M, which when the pinwheel is up against disk K is slipped on spindle J and bears against the opposite face of the pinwheel, forcing the other face 60 against disk K and serving to hold the pinwheel properly in place upon the shaft, as will be clearly seen upon reference to Fig. 2. After the pinwheel is adjusted upon the spindle the head end of the spindle is seated in 65 socket F and the pointed end is passed down into the seat or recess G, slots H and I serving to direct or guide the point to its position in socket G. A pinwheel mounted in this manner rotates very freely, and the full effect 70 thereof is had from the moment the combustible matter is ignited. Arm A will have sufficient spring to properly hold the spindle in position, but at the same time will enable the operator to readily withdraw the spindle and 75 replace it when a new pinwheel has been positioned thereon.

It is manifest that various modifications of the device may be made. For instance, a 80 needle need not necessarily be employed for the shaft or spindle. In practice, however, it is found to afford a strong and ready means, the pointed end thereof facilitating the positioning of the removable disk or button M.

While it is advisable to have disk K rigidly secured to the spindle, still it will be seen that even this is not necessary, as both buttons or disks K and M may be made removable or either of them rigid. So, too, any material 90 other than cork may be used for the removable disk, and the end of member C may be finished in any manner other than that shown to enable it to be readily attached to a suitable permanent support.

Having thus described my invention, what I claim is—

1. In a device of the character described, the combination of a suitable supporting device comprising two members connected at 100 one end only and being open or separated from each other at their opposite ends, one of said members being in the form of a spring-arm, and each member having a socket or

seat formed therein adjacent to its free end; a shaft or spindle mounted intermediate said members and having its ends bearing in said sockets or seats; and means carried by said shaft for removably maintaining in position a pinwheel mounted thereon.

5. In a device of the character described, the combination of a suitable open spring-support having sockets or seats formed in its 10 opposite faces adjacent to the free ends of said support; means for attaching said support to an object; a spindle or shaft having its ends bearing in said sockets and normally held therein by the spring action of the support; and means attached to said shaft or 15 spindle for removably securing a pinwheel thereon.

3. In a device of the character described, the combination of an open U-shaped support, one arm of said support being extended 20 clear of the other and provided with means for securing the whole to a permanent or fixed object; a shaft or spindle mounted in seats or sockets formed in the opposite faces 25 of the arms of said support adjacent to the free ends thereof; and means carried by the shaft for maintaining a pinwheel in proper position thereon.

4. In a device of the character described, 30 the combination of a U-shaped member, one arm of which extends to a point clear of the other and is provided with means for attaching it to a permanent object or support; a shaft or spindle seated within sockets formed 35 in the opposite faces of the arms of said U-shaped member, one of said arms having grooves or channels formed in its face adjacent to the socket or recess; a disk secured to the shaft; and a removable clamping member also 40 mounted on the spindle.

5. In a device of the character described, the combination of a U-shaped member, one arm of which extends to a point clear of the other and is bent at right angles to form an 45 attaching-point; a shaft or spindle seated in

sockets or recesses formed in the opposite faces of the arms of said U-shaped member, one of said arms having grooves or channels formed in its face and leading to the socket or recess; a disk permanently secured to said 50 shaft; and a clamping member detachably mounted upon said shaft.

6. In a device of the character described, the combination of an open U-shaped bracket having sockets formed in the opposite faces 55 thereof adjacent to the ends, one of said sockets having a lead-groove extending thereto; and a detachable spindle for supporting a pinwheel, said spindle being adapted to be seated in the sockets, the lead-groove facilitating 60 the insertion of one end of the spindle into the socket adjacent to the groove.

7. In a device of the character described, the combination of an open U-shaped spring-arm bracket having sockets formed in the adjacent faces of the arms near the ends thereof, one of said sockets having a lead-groove 65 extending thereto; and a detachable spindle for supporting a pinwheel, said spindle being adapted to be seated in the sockets, the 70 lead-groove facilitating the insertion of one end of the spindle into the socket adjacent to the groove.

8. In a device of the character described, the combination of an open U-shaped support, one arm of said support being extended 75 above the other and provided with a securing-prong; a shaft or spindle mounted in the seats or sockets formed in the opposite faces of said support; and means carried by the 80 shaft for removably maintaining a pinwheel in proper position thereon.

In testimony whereof I have signed my name to this specification in the presence of two subscribing witnesses.

JAMES E. BENEDICT.
